Primary Examiner — Richard Kearney

Assistant Examiner — Landon Thomas Cassell

(74) Attorney, Agent, or Firm — Lightfoot & Alford PLLC

(57) **CLAIM**

The ornamental design for the tourniquet as shown and described.

DESCRIPTION

FIG. 1 is a top side perspective view of the tourniquet showing our new design;

FIG. 2 is a bottom side perspective view thereof;

FIG. 3 is a left side view thereof;

FIG. 4 is a right side view thereof;

FIG. 5 is a top side view thereof;

FIG. 6 is a bottom side view thereof;

FIG. 7 is a back side view thereof; and,

FIG. 8 is a front side view thereof.

The broken lines illustrate portions of the tourniquet that form no part of the claimed design.

1 Claim, 7 Drawing Sheets
